WINDOW SHADE

Samuel E. Snyder, Brooklyn, N. Y.

Application December 9, 1932, Serial No. 646,542,
and in Canada December 17, 1931

3 Claims. (Cl. 156—27)

This invention relates to new and useful improvements in window shades and more particularly to spring-actuated shades and an object of the invention is to provide a novel arrangement, whereby a shade of adjustable length may be suspended at any desired position in relation to the window opening in a manner to provide privacy and at the same time admit light and air from the upper part of the window.

10 A further object is to provide a suitable means, whereby a spring roller and its attached shade may be operably borne and in movable relation to the window opening.

A still further object is in the provision of a 15 stationary spring roller adapted to actuate the movable spring roller and its attached shade in relation to the window opening and at the same time having sufficient tension not to be effected by the tensioning of the spring in the shade roller.

20 A yet further object is in the provision of the novel winding cones which coil and uncoil the flexible connections from the shade roller device in a manner to equalize the leverage upon the roller in relation to the spring tension of the 25 roller.

Another object of the invention is to provide an attachment for governing the rotation of the supporting roller of the window shade.

Another object of this invention is to provide a 30 device of the character described which, when attached to the conventional type of spring roller will serve to govern the rotation of the roller when winding the shade suspending means thereon.

35 Another object of this invention is to provide a device of the character described, which will allow free unwinding of the shade suspending means.

Other objects and many of the attendant advantages will be readily appreciated as the invention becomes better understood from a consideration of the illustrative embodiments of the same and for which purpose such descriptive drawings have been hereto appended, wherein:—

45 Fig. 1 is an elevation of a window and shade having the invention attached thereto.

Fig. 2 is an enlarged detail view of the stationary roller having the winding cone and rotation governing device attached thereto.

50 Fig. 3 is a detailed view of the spring roller.

Fig. 4 is a longitudinal sectional view through the governing device.

Fig. 5 is a cross sectional view of the same.

55 Fig. 6 is an end view of the stationary roller.

Fig. 7 is an end view of the spring roller and support therefor.

Fig. 8 is a perspective view of the same.

Fig. 9 is an alternative design of trunnion.

Referring more in detail to the drawings in 60 which similar reference numerals designate the corresponding parts:

It will be seen that the window 15 is normally covered by the shade 16 produced of suitable, 65 tractable material 17 attached to the spring roller 18 in a manner to normally wind thereon by the tension of the spring. The spring roller 18 and its attached shade is operably suspended by the bar 19 having end members 20 secured on the said bar by set screws 20a, said end members having depending ears 21 and 22. On the ear 21 is produced a round protrusion 23 adapted to bear the rotatably orifice, whilst in the ear 22 is a rectangular protrusion 24 adapted to engage the non-rotatable orifice. The alternate design 75 shown in Fig. 9 provides a threaded trunnion having a screw driver slot in the end thereof as a more convenient means of releasing the shade roller. These protrusions are projected inwards into the roller thus presenting a flat outside surface on the members 20 which will provide a great 80 advantage where curtains or drapes are used on the window.

The shade 16 is suspended in adjustable relation to the window opening 15 by linen cords 26 85 or the like which are attached to the stationary roller 27 in a suitable manner at 28 and depend therefrom to engage the eyes 29 which project from the shade bearing bar 20.

The stationary spring roller 27 is rotatably 90 borne by the common brackets 30 which are provided with ears 31 adapted to receive the rotatable trunnion 32 and non-rotatable trunnion 33 in common form. Mounted upon each end extremity of the roller 27 is a member 34 having the 95 form of a frustum of a cone, hereafter termed cone, which cones have spiral grooves or threads 35 produced in their exterior surface and adapted to coil and uncoil the cords 26 in even, spaced turns in operation. Each of these cones 34 is also provided with an integral annular flange 35a which is 100 preferably of dimensions equal to the largest diameter of the cone and adapted to prevent over-winding of the cords 26 into the trunnions and consequently jam.

The cord 36 is secured to the member 37 on the bar 19 the said member 37 having a curved portion 37a projecting from the same. When the cord is pulled to lower the shade the curved portion 37a will rest on the rolled shade 16. This 110

obviates the necessity of using large diameter tubes when the device is used on a wide window.

The cord 38 is secured to the eye 39 of the filler stick 40 at the free end of the shade material 17 5 in a manner to adjust the shade over the desired space of the window.

With this novel arrangement, it is obvious any desired portion of the window opening 15 may be covered, and that when the shade 16 is at the top 10 of the window opening 5 and the tension spring of roller 27 is in relatively unwound condition, the cords 26 are then engaging the cones 35 at their smaller diameter and nearer the axis of the roller. Therefore, the leverage is relatively less in proportion to the strength of the spring. Again, 15 when the shade 16 is at the bottom of the window opening and the tension spring of roller 27 is in relatively wound up condition, then the cords 26 are engaging the cones 35 at their larger diameter 20 and further from the axis of the roller and the leverage is greater in proportionate relation to the strength of the spring. Accordingly by this novel cone arrangement, the leverage is equalized in proportion to the variation of the spring tension 25 of roller 27.

Attached to the stationary roller 27 is the rotation governor which comprises two hard rubber collars 41 over which tube 42 is mounted and secured by clamps 43 in such a manner that collars 41 constitute ends for the tube 42. One of the clamp 43 is provided with an arm 44 of soft metal, which arm is deflected to lie adjacent the window moulding 45 and be secured thereto by screws 46. A tongue 47 is punched outwardly from the tube 35 42 intermediate the ends thereof, in a manner to constitute a fissure 48.

A collar 49 is mounted around the spring roller 27 within the tube 42 in frictional contact therewith, and a hook 50 is connected thereto by spring 51. The tension of the spring 51 causes the said hook to lie against the collar 49 when the spring roller 27 is still. The collar 49 is provided with a friction adjustment which comprises a screw 52 threaded into the said collar and bearing 45 against a thin metallic plate 52a and causing the said plate to bear against the spring roller 27. An orifice 53 is provided in the tube 42 to permit the same to be adjusted.

The collar 49 is retained centrally in the tube 50 by means of two U-shaped guide members 54 secured in the spring roller 27. This serves to keep the hook 50 in alignment with the fissure 48.

In operation it will be seen that the tube 42 and collars 41 are held in fixed relation to the window-moulding 45 with the spring roller 27 extending therethrough. As the shade suspending means is unwound from the roller 27 causing its rotation, the tight fitting collar 49 also ro-

tates with its attached hook 50 in such a direction that the hook will not engage with the fissure 48.

When the shade suspending means is being wound up, by the action of the spring roller, the hook will gradually leave its position against the collar 49 due to centrifugal force and should the speed of rotation be great enough the hook 50 will engage the fissure 48 in a manner to hold the collar 49 rigid to the stationary tube 42 when the collar 49 will frictionally check the rotating speed of the roller and thereby serve to prevent damage to the roller shade.

It will be obvious from the foregoing description that this invention is a great improvement in controlling means for window shades and while the preferred embodiment has been disclosed, yet it is to be understood that minor changes in the details of construction and combination may be resorted to within the scope of what is claimed without departing from the spirit of the invention.

I claim:—

1. In combination with a spring roller for window shades, a governor comprising a tube loosely mounted on said roller in spaced relation thereto, means fixedly securing said tube to the window moulding, a fissure formed in said tube, a collar mounted on said roller within said tube, adjusting means carried by said collar for securing the collar in frictional contact with the roller, and a hook suspended from said collar for engagement with the fissure of said tube through the action of centrifugal force upon rotation of said collar.

2. In combination with a spring roller for window shades, a governor comprising a tube loosely mounted on said roller in spaced relation thereto, means fixedly securing said tube to the window moulding, a fissure formed in said tube, a collar mounted on said roller within said tube having frictional contact with the roller, and a hook suspended from said collar adapted to normally lie against said collar, said hook being movable through the action of centrifugal force into engagement with the fissure of said tube upon rotation of the roller.

3. In combination with a spring roller for window shades, a governor comprising a tube loosely mounted on said roller in spaced relation thereto, means fixedly securing said tube to the window moulding, a fissure formed in said tube, a collar mounted on said roller within said tube, a set screw carried by said collar for adjusting the collar in frictional contact with the roller, and a hook suspended from said collar for engagement with the fissure in said tube through the action of centrifugal force upon rotation of the roller.

SAMUEL E. SNYDER.
